UNITED STATES PATENT OFFICE.

MYRTLE P. BROWN, OF KANSAS CITY, MISSOURI.

DESIGN FOR AN UNDERGARMENT.

54,723.

Specification for Design.

Patented Mar. 23, 1920.

Application filed September 29, 1919. Serial No. 327,333. Term of patent 14 years.

To all whom it may concern:

Be it known that I, MYRTLE P. BROWN, a citizen of the United States, and a resident of Kansas City, Jackson county, State of Missouri, have invented a new, original, and ornamental Design for an Undergarment, of which the following is a specification, reference being had to the accompanying drawing, forming a part thereof.

In the said drawing:

Fig. 2, is a side view of the same.

Fig. 3, is a front view of the same.

I claim:

The ornamental design for an undergarment as shown.

MYRTLE P. BROWN.
